UNITED STATES PATENT OFFICE.

ENOCH P. STEVENS, OF MORGAN PARK, CHICAGO, ILLINOIS; MARY ANN STEVENS
EXECUTRIX OF SAID ENOCH P. STEVENS, DECEASED.

KILN.

Application filed May 11, 1921. Serial No. 468,646.

To all whom it may concern:

Be it known that I, ENOCH P. STEVENS, a citizen of the United States, residing at Morgan Park, Chicago, in the county of Cook and State of Illinois, have invented certain new and useful Improvements in Kilns, of which the following is a specification.

This invention relates to kilns for the heat treatment of materials. It is designed primarily for burning bricks or other objects of refractory material, but it is adapted for many other uses.

The object of the invention is to provide a highly efficient heating apparatus for kilns which will insure continuity of heat of desired degree until the heat treatment is finished, and which will utilize a large proportion of the heat of discharged products of combustion for raising the temperature of the combustion supporting medium.

The invention proceeds upon the principle of delivering fuel and combustion supporting medium into a kiln, preferably at the center and in the upper portion thereof, and then discharging the waste products of combustion from the lower portion thereof; the discharge flues for the products of combustion being subdivided into a plurality of channels which, as they become hot, are adapted to be severally interposed as a portion of the conduit through which combustion supporting medium reaches the kiln.

The invention consists in the novel arrangement of the elements combined in accordance with the above-stated principle as well as in certain constructions incident thereto, as set forth in the subjoined description and particularly pointed out in the appended claims.

In the accompanying drawings, in which one embodiment of the invention is disclosed by way of illustration.

Figure 1 is a plan view of a kiln.

Figure 2 is a vertical central section of the same; and Figure 3 is a schematic plan of means for simultaneously and reciprocally operating a plurality of valves which control the paths of combustion supporting medium and products of combustion.

1 represents a kiln which is preferably cylindrical in form, and which has any suitable form of top closure 2 and sealed charging opening 3. Centrally located in the

kiln 1 is a burner 4 adapted to discharge burning fuel mixture, such, for instance, as crude oil supported by hot air, and 5 represents an apertured floor of the kiln through which products of combustion may escape into the sub-floor spaces 6 which communicate with a discharge flue 7 that is subdivided into two leads, respectively controlled by valves 7^a, 7^b and adapted to discharge into the checker chambers 8, 8^a, discharging, subject to the control of valves 9^a, 9^b, into the stack 9. 10 represents a source of combustion supporting medium, such, for instance, as an air shaft which communicates through air trunk 11 and valved ports 12, 12^a with the respective checker chambers 8, 8^a. 13 represents a flue which supplies the burner 4 with combustion supporting medium, and is adapted to receive hot air through valved ports 14, 14^a from the respective checker chambers 8, 8^a. The fuel supply for the burner 4 preferably consists of a nozzle 15 to which fluid fuel is supplied through a pipe 16 from some suitable source, such, for instance, as an elevated tank 17. Surrounding that portion of the pipe 16 which runs with the hot air flue 13 is a jacket 18 which, while transmitting sufficient heat to keep the fuel in good fluid state, prevents the fuel from vaporizing in the pipe 16 by admitting around the latter a constant flow of air received from the pit 19 at atmospheric temperature, and delivered around the nozzle 15 as a part of the combustion supporting medium, although not in sufficient proportion to cool the main body of combustion supporting air below the point of efficiency.

In operating the kiln equipped as above described, one of the checker chambers, for instance, chamber 8, is introduced as a means of communication for waste products of combustion from the flue 7 to the stack 9 by opening the valves 7^a and 9^a and closing the valve 12, while the other checker chamber 8^a is introduced as a part of the conduit for the supply of air from shaft 10 to hot air flue 13 for supporting combustion by closing the valves 7^b and 9^b and opening the valves 12^a and 14^a. When checker chamber 8 has been subjected to the products of combustion until its checker work has acquired approximately the temperature of the products of combustion, valves 7^a and 9^a are

closed and valves 12 and 14 are opened and simultaneously valves 7^a and 9^b are opened and valves 12^a and 14^a are closed, so that now the combustion-supporting air will flow from shaft 10 past valve 12 to the checker-work of the chamber 8, where it will take up heat of the latter and pass thence through valved port 14 into the hot air flue 13 and to the burner 4, and while the air is thus flowing the products of combustion will be raising the temperature of the checkerwork in the chamber 8^a. When the checkerwork in chamber 8 has cooled down and that in chamber 8^a has become heated, the valves are again shifted to again change the connection of the chambers, and this operation continues until the heat treatment in the kiln is completed and the combustion of fuel interrupted.

20 In practice pyrometers will be introduced into the chambers 8, 8^a, as suggested at 20 and 20^a and connected up with a suitable indicator such, for instance, as the bell circuit 21 in a manner to indicate to the operator when the shifting of the valves is to be made.

Any suitable means may be employed for insuring the action of the pairs of valves reciprocally with each other and with other valves of the system with which they must alternate in action. One arrangement for accomplishing this purpose is suggested schematically in Figure 3, wherein 22 is a main shaft adapted to be rotated in opposite directions by a suitable crank, while branch shafts are provided equipped, respectively, with pulleys 24^a and 24^b acting in opposite directions upon chains or other flexible connectors 26, 26^a of valves 7^a and 14, and pulleys 25^a and 25^b acting oppositely upon flexible connectors of valves 7^b and 14^a. Shafts 24 and 25 are connected through bevel gearing 28 with shaft 22 so that when shaft 22 is rotated, rotation will be imparted to branch shafts 24 and 25 in opposite directions to each other, and each branch shaft will develop opposite movements in two valves which it controls. Thus, valves 7^a and 7^b will alternately open and close and valves 14 and 14^a will likewise alternate in their action with valve 7^a and with each other.

29 represents a pulley that has a flexible connector 30 having its intermediate portion wound around said pulley and its ends connected to the respective valves 12 and 12^a so that as shaft 22 rotates in opposite directions valves 12 and 12^a will be alternately opened and closed, and this opening and closing will be simultaneous with and reciprocal to valves in the groups represented by 7^a, 7^b, 14 and 14^a, it being merely a matter of selection of direction of winding of the flexible connector 30 to accomplish this purpose.

31 and 32 represent another pair of branch

shafts carrying, respectively, pulleys 31^a and 32^a which are driven in opposite directions by the shaft 22, and being connected by flexible connectors 31^b, 32^b with the valves 9^a and 9^b to insure reciprocal action in said valves and in proper relationship to the action of the valves 12, 12^a in the groups 7^a, 7^b and 14, 14^a. Thus, it is merely necessary for the operator to throw the crank 23 from one to the other of its two limits of movement each time the indicator sounds in order to insure proper operation of the kiln. Obviously, this operation may be insured by time clock or other telltale arrangement commonly used for insuring attention of an operative under similar circumstances.

While the embodiment of my invention selected for purposes of illustration is designed for handling fuel of such form as can be introduced through a pipe, it is to be understood that the underlying features of my invention are equally applicable to installations embodying means for handling solid fuels through means of stokers or the like.

I claim:

1. In a kiln, a hot air flue a pipe for supplying liquid fuel to the kiln passing through said hot air flue, and a cooling jacket surrounding said pipe within said hot air flue.

2. In a kiln, a hot air flue, a pipe for supplying liquid fuel to the kiln passing through said hot air flue, and a cooling jacket surrounding said pipe within said hot air flue, having its ends opened, respectively, to a fresh air supply and to the kiln.

3. A kiln, comprising a chamber having a center flue extending to a region near the top of said chamber, said chamber having an apertured floor, means extending from said chamber providing a pair of checkered passageways communicating with said chamber through said floor, a source of air supply, a stack having communication with said checkered passageways, and means operable by common control for reversing the connections of said chambers to said source of air supply and said stack.

4. A kiln, comprising a chamber having a center flue extending to a region near the top of said chamber, said chamber having an apertured floor, means extending from said chamber providing a pair of checkered passageways communicating with said chamber through said floor, and fuel supply means passing through said flue at a region between said checkered passageways.

5. A kiln, comprising a chamber having a center flue extending to a region near the top of said chamber, said chamber having an apertured floor, means extending from said chamber providing a pair of checkered passageways communicating with said chamber through said floor, and fuel supply means passing through said flue at a region

between said checkered passageways, said fuel supply means having means providing a cooling jacket.

6. A kiln, comprising a cylindrical chamber having an upstanding flue extending to a region near the top thereof, said chamber having a floor provided with apertures distributed around said floor, said chamber being provided with a space therebelow, and means extending from said chamber providing a pair of parallel checkered passageways communicating with said space.

7. A kiln, comprising a cylindrical chamber having an upstanding flue extending to a region near the top thereof, said chamber having a floor provided with apertures distributed around said floor, said chamber being provided with a space therebelow, means extending from said chamber providing a pair of parallel checkered passageways communicating with said space, and fuel supply means extending from the exterior of said chamber to the interior thereof through said flue, said fuel supply means being located between said checkered passageways.

8. A kiln, comprising a cylindrical chamber having an upstanding flue extending to a region near the top thereof, said chamber having a floor provided with apertures distributed around said floor, said chamber being provided with a space therebelow, means extending from said chamber providing a pair of parallel checkered passageways communicating with said space, and fuel supply means extending from the exterior of said chamber to the interior thereof through said flue, said fuel supply means being located between said checkered passageways, and being enclosed within a jacket which communicates with the outside air and which encloses said fuel supply means to a point adjacent to the top of said flue.

45 9. A kiln, comprising a cylindrical chamber having a center flue extending to a

region near the top of said chamber, said chamber having an apertured floor, and a pipe located within said flue adapted to lead liquid fuel to a point adjacent to the top of said flue.

10. A kiln, comprising a cylindrical chamber having a center flue extending to a region near the top of said chamber, said chamber having an apertured floor, and a pipe located within said flue adapted to lead liquid fuel to a point adjacent to the top of said flue, said pipe being provided with a cooling jacket extending from a point in communication with the outside air to a point adjacent to the top of said flue.

11. A kiln, comprising a chamber having a center flue extending to a region close to the top thereof and an apertured floor having a space therebelow, means extending from said chamber providing a pair of parallel adjacent checkered passageways, a source of air supply and a stack communicating with said passageways at points distant from said chamber, valves controlling communication between said chambers and said flue at points adjacent to said chamber, valves for controlling the connections of said source of air supply and said stack with said passageways, and means operable in common for controlling said valves to reverse the direction of flow through said passageways.

12. A kiln, comprising a chamber having a center flue and an apertured floor, said floor having a space therebelow, said flue providing a conduit for heated air and fuel, and means extending from said chamber providing a pair of parallel adjacent checkered passageways, said flue communicating with said passageways at a region between said passageways.

Signed at Chicago, Illinois, this 23rd day of April, 1921.

ENOCH P. STEVENS.
